UNITED STATES PATENT OFFICE.

JOHN DONEY, OF PEN ARGYLE, PENNSYLVANIA.

FEED-SCREW ADJUSTMENT.

SPECIFICATION forming part of Letters Patent No. 697,332, dated April 8, 1902.

Application filed November 30, 1901. Serial No. 84,189. (No model.)

To all whom it may concern:

Be it known that I, JOHN DONEY, a citizen of the United States, residing at Pen Argyle, in the county of Northampton and State of Pennsylvania, have invented a new and useful Feed-Screw Adjustment, of which the following is a specification.

This invention relates generally to feed-screws, and more particularly to an improved 10 adjusting means whereby the wear of the said screw is taken up; and the object of the invention is to provide an exceedingly cheap and simple adjusting means capable of use in connection with a feed-screw used in connection 15 with any machine or drill.

The invention consists in the novel features of construction and combination hereinafter fully described, and pointed out in the claims.

In the drawings forming a part of this specification, Figure 1 is a sectional view of the feed-screw adjustment. Fig. 2 is a side elevation of the feed-nut, and Fig. 2^a a top plan view of the jam-nut. Fig. 3 is a side elevation of the adjusting-nut, and Fig. 3^a is a top 25 plan view of the same, and Fig. 4 is a top plan view of the intermediate or jam nut.

Referring to the drawings, A indicates the ordinary feed-screw, which in the present instance is shown as forming a part of a drill. 30 This feed-screw passes through a feed-nut B, which rests within a collar or sleeve C, said nut extending a considerable distance above the said collar or sleeve, and said extending portion is externally threaded, as shown at B'.

35 A jam-nut D is screwed upon the threaded portion of the feed-nut and bears against the upper end of the collar or sleeve C, and an adjusting-nut E is arranged upon the feed-screw above the upper end of the feed-nut, 40 said adjusting-nut being recessed at its lower end, as shown at E', in order to receive the upper end of the said feed-nut, said recessed portion of the adjusting-nut being threaded both internally and externally, as shown at 45 E² and E³, respectively, the threaded portion B' of the feed-nut engaging the interior threads E², while an intermediate jam-nut or threaded collar F is secured upon the exterior threaded portion E', said intermediate jam-nut or collar 50 F bearing upon the jam-nut D, said nut or collar F serving to lock all of the parts in their adjusted positions. The adjusting-nut E is for the purpose of taking up the wear of the screw A, and when it is desired to take up

such wear the nut F is loosened and the adjusting-nut E turned the necessary amount to take up the said wear, and the nut F is then retightened and all the parts will be held in their proper relative positions, and an accurate feed of the screw can then be had. Inasmuch as the parts when so locked virtually constitute one complete nut, by means of the adjustment herein shown and described I am enabled to quickly and easily adjust the parts with great accuracy, so that any amount of 60 wear can be taken up, and by means of such device I am enabled to use a screw for a greater length of time than ordinarily, inasmuch as by taking up the wear the use of said screw can be continued until the threads of 70 the screw are completely worn out.

Having thus fully described my invention, what I claim as new, and desire to secure by Letters Patent, is—

1. The combination of a feed-nut, the upper end of which is externally threaded, an adjusting-nut arranged above the feed-nut and adjustable thereon, and means for locking the adjusting-nut, as set forth. 75

2. The combination of a feed-nut, the upper end of which is threaded externally, an adjusting-nut arranged upon the threaded end of said feed-nut, and the locking-nut for securely locking the adjusting-nut in position, as set forth. 80

3. The combination with the feed-nut threaded at its upper end, of the adjusting-nut arranged upon said threaded end, a jam-nut arranged upon the threaded end of the feed-nut and below the adjusting-nut, and the locking-nut arranged upon the adjusting-nut and adapted to bear upon the jam-nut, substantially as set forth. 90

4. The combination of a feed-nut, the upper portion of which is externally threaded, an adjusting-nut, the lower end of which is recessed, said recessed portion being internally and externally threaded, the upper end of the feed-nut engaging the interior threads, a jam-nut arranged upon the threaded portion of the feed-nut and below the adjusting-nut, and a locking-nut screwed upon the adjusting-nut and bearing upon the jam-nut, substantially as set forth. 95

JOHN DONEY.
